STORAGE CONTAINER FOR LETTUCE
OR THE LIKEJames B. Swett, 8 Devonshire Drive,
Barrington, R.I. 02806

Continuation-in-part of design applications Ser. No. 5,003, Dec. 12, 1966, now Patent No. 212,033, dated Aug. 20, 1968 and Ser. No. 5,008, Dec. 12, 1966, both of which were divisions of design application Ser. No. 906, Feb. 3, 1966, now abandoned. This application Oct. 2, 1967, Ser. No. 9,184

Term of patent 14 years

Int. Cl. D7—07

U.S. Cl. D7—76

FIG. 1

FIG. 2

FIG. 3

FIG. 5

FIG. 1 is a perspective view of a storage container for lettuce or the like showing my new design with the cover removed;

FIG. 2 is a similar view with the cover in place;

FIG. 3 is a top plan view of FIG. 1;

FIG. 4 is a bottom view of FIG. 1; and

FIG. 5 is an enlarged scale elevational view, partly in section, and with portions omitted for clarity of illustration.

This application is a continuation-in-part of applications D. 5,003, filed Dec. 12, 1966, now Pat. D. 212,033 of Aug. 20, 1968, and D. 5,008, filed Dec. 12, 1966, both of which were divisions of application D. 906, filed Feb. 3, 1966, and now abandoned.

I claim:

The ornamental design for a storage container for lettuce or the like, substantially as shown and described.
